UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A CANOPY EXTENSION FOR SUPPORTING CHAIN FIXTURES.

48,523.

Specification for Design.

Patented Feb. 8, 1916.

Application filed December 16, 1915. Serial No. 67,284. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Canopy Extension for Supporting Chain Fixtures, of which the following is a specification, reference being had to the accompanying drawing, forming part thereof.

The figure is a perspective view of a canopy extension for supporting chain fixtures, showing my new design.

I claim:

The ornamental design for a canopy extension for supporting chain fixtures, as shown.

CHARLES E. JONES.
